COVER FOR A PICK-UP TRUCK BED

William T. Keurst, Miami, Fla. (½ Scott Products Corp., 3399 Ponce de Leon Blvd., Coral Gables, Fla. 33134)

Filed Apr. 20, 1967, Ser. No. 6,767

Term of patent 14 years

(Cl. D14—27)

FIG. 1

FIG. 2

FIG. 3

FIG. 4

I claim:

The ornamental design for a cover for a pick-up truck bed, as shown and described.
